Primary Examiner — Karen E Eldridge Powers(57) **CLAIM**

The ornamental design for an electric toothbrush handle, as shown and described.

DESCRIPTION

FIG. 1 is a perspective view of an electric toothbrush handle according to the new design;

FIG. 2 is a front view thereof;

FIG. 3 is a rear view thereof;

FIG. 4 is a top view thereof;

FIG. 5 is a bottom view thereof;

FIG. 6 is a right side view thereof; and,

FIG. 7 is a left side view thereof.

All broken lines shown in the drawings are for the purpose of illustrating environmental structure and form no part of the claimed design.
